UNITED STATES PATENT OFFICE.

GUSTAV J. SELK, OF BEND, OREGON.

AUTOMATIC SAFETY-STOP FOR STEAM-ENGINES.

1,381,756.

Specification of Letters Patent. Patented June 14, 1921.

Application filed January 24, 1918. Serial No. 213,518.

To all whom it may concern:

Be it known that I, GUSTAV J. SELK, a citizen of the United States, residing at Bend, in the county of Crook and State of Oregon, have invented certain new and useful Improvements in Automatic Safety-Stops for Steam-Engines, of which the following is a specification.

This invention relates to improvements 10 in a safety device for a steam engine and the invention has more especial reference to an improved automatic safety stop or cut-off particularly adapted for use in connection with steam engines of the "Corliss" type.

15 The invention has for its dominant object to provide an automatic stop which when arranged on an engine and connected with the speed governing means therefor will serve to interrupt the supply of motive fluid 20 to the working parts of the engine should the driving belt of the governor be broken or other abnormal conditions be present whereby the speed at which the governor is normally operated will be lessened.

25 Other independent objects are to provide features of construction of portions of the device which tend toward the attainment of the above aim irrespective of the relation in which they are used.

30 Other objects will be in part obvious and in part pointed out hereinafter.

The invention accordingly consists in the features of construction, combination of elements, and arrangement of parts which 35 will be exemplified in the description hereinafter set forth, and the scope of the application of which will be indicated in the following claims.

In the accompanying drawings, wherein 40 is shown one of various possible embodiments of my invention;

Figure 1 is a front elevation of the device applied to the speed governing means of an engine,

45 Fig. 2 is a rear elevation of the same,

Fig. 3 is an elevation of the throttle valve having the trip valve engaged therewith,

Fig. 4 is a rear elevation of the governor stand positioned relative to the throttle 50 valve and the controlling valves of the engine, showing by full lines the normal position of the device and by dotted lines the working position thereof and the controlling valves of the engine closed.

Fig. 5 is a detail in perspective of the cam lever.

Fig. 6 is a view showing the set position of the mechanism before the safety stop is tripped.

Similar reference characters refer to similar parts throughout the several views of the drawings.

Referring to the drawings in detail, A designates generally the vertical stand post or tubular column of a ball weight centrifugal speed governor, usually adapted for use with stationary steam engines, and in this instance with the "Corliss" type of steam engine, and within the stand post or column is arranged the rotary governor driving shaft B, which at its upper end is fitted with a suitable head having pivotally connected therewith the usual opposed swinging governor arms C carrying the ball weight members D the latter being located at or near the free ends of said arms, while surrounding the governor shaft B is the sliding sleeve E having the toggle link connections F with the governor arms C so that on movement of said governor arms inwardly toward or outwardly away from each other in the operation of the governor the sleeve E will be vertically adjusted on the rotary governor shaft B accordingly.

The governor shaft B is connected in any suitable manner with the driving parts of the engine, either through the medium of a driven shaft and gear connections or through a driving belt (not shown) while the sleeve E is engaged with a governor stem G operatively connected with the motive fluid controlling valves of the engine, whereby the speed of the driving parts of said engine and the operation of the latter will be controlled automatically on the activity of the governor in the working thereof in the usual well-known manner.

Co-acting with the governor is the automatic safety stop device, which comprises a bracket 4 made fast in any suitable manner upon the stand post or column A and includes opposed laterally extending hangers 5 on which are swingingly supported rocking arms 2 and 3, having toothed segments 6 and 7 respectively which are in meshing engagement with each other, the arm 2 being fixed to a stub shaft 6^a journaled transversely in one of the hangers 5, while the

arm 3 is loosely engaged for rocking movement upon a stub shaft 7^a journaled transversely in the other hanger 5. Secured to the stub shaft 6^a and loosely supported upon 5 the stub shaft 7^a are weighted trip arms 8 and 9 respectively. The arm 8 is fitted with an auxiliary weighted element 10, while the arm 9 is fitted with a main weighted element 10'. On the arm 9 is a trip horn 10 11 formed with a beveled tripping nose 12 for coöperation with a tripping latch or catch 13, pivotally mounted upon a setting rod 14, the latter being formed with an elongated slot 15, receiving a guide bolt 16 15 carried by a guide 17 made fast to one of the hangers 5. The setting rod 14 is pivotally engaged with a spring 18 fixed to a throttle valve casing H shown in Fig. 3 of the drawings, the stem 20 of the throttle 20 valve in said casing H being manually operated and is fitted or formed with an abutment collar 21 constituting a trip device to co-act with the setting rod 14, so that when the stem 20 is moved outwardly of the valve 25 casing H for opening the valve therein, whereby steam will be supplied or admitted to the engine (not shown) for the operation of the latter, the said abutment collar 21 will engage with the setting rod 14 for 30 shifting the same against the resistance of the spring 18, and in this shifting movement of said rod the latch or catch 13 is positioned for operation with the safety stop device, hereinafter more fully described. 35 Carried upon the governor stem G is a tripping cleat or cross head 23 adapted for tripping engagement with the latch or catch 13 on movement of the governor stem G a predetermined distance. The latch or catch 40 13 when in its operative or set position relative to the safety stop device is arranged so that on moving the swinging arms 8 and 9 to the vertical or perpendicular position, the horn 11 on the arm 9 will ride over the 45 said latch or catch 13. Now when the tripping cleat 23 rides down and strikes the projecting end of the catch 13, the inclined face 12 coacts with the left hand end 13^a of the member 13 and prevents clockwise rotation thereof. This initial movement will 50 throw the arm 9 past the dead center and as it falls outwardly and downwardly the arm 8 moves simultaneously therewith under the action of the trip and auxiliary 55 weights carried by said arm for the operation of the safety device in a manner presently to be described.

On the swinging arm 3, having the toothed sector 7 is a striking head or member 22, which projects into the path of movement of the arm 9 so that when the latter is shifted from vertical position after moving a predetermined distance, it will engage the head or member 22 to cause the 60 65 arm 3 to be shifted or moved simultaneously

with said arm 9 and on movement of the arm 3 through the meshing engagement of the sectors 6 and 7 with each other, the arm 8 will also be shifted from perpendicular position through the medium of the arm 70 2 and the movement of these arms 8 and 9 from normal perpendicular position shown in Fig. 2, when the automatic stop device is inactive to the position shown in Fig. 1 of said drawings renders the said stop 75 device active for the purpose presently described.

Connected with the stub shaft 6^a is a compound throw lever 24, which latter is pivoted at 25 to the guide 17 while fixed to 80 the stub shaft 7^a is a rocking lever 26, the latter being connected to the stem G of the governor through the medium of a coupling bolt 27 so that on the shifting of the said stem G in the operation of the governor 85 the arm 26 will be moved thereby, the lever 24 being located relative to the arm 26 to act upon the same on the swinging of the arms 8 and 9 of the safety stop device for a purpose hereinafter described. 90

Carried upon the stub shaft 7^a adjacent to the arm 3 is a rocking beam 28, which latter is suitably connected with the arm 3 for movement therewith so that on the turning of the latter, said beam 28 will be 95 actuated thereby.

Pivoted to the ends of the rocking beam 28 are valve actuated rods 29, which are also connected to the controlling valves of the engine through the medium of the rocker 100 arms 30, whereby on the shifting of the rods 29, the controlling valves of the engine will be opened and closed and adjusted for regulating the operation of said engine.

The movement or dropping of the arms 8 and 9 from vertical position shown in Figs. 2 and 4 of the drawings, to the position shown by full lines in Fig. 1 and by dotted lines in Fig. 4, in the operation of the automatic safety stop device effects the action 110 of the lever 24 upon the arm 26, connected to the governor stem G so as to abnormally burden the governor and also the rocking beam 28 is simultaneously actuated for the shifting of the rods 29 connected with the 115 engine controlling valves to close the latter and thus stop the working of the engine.

When the weighted arms 8 and 9 are moved from perpendicular position outwardly and downwardly an upward thrust 120 upon the arm 26 is had through the compound lever 24, under the action of the weights 10 carried by said arms 8 and 9 and thus the governor stem G will be raised for abnormally burdening the governor at the 125 time that the controlling valves are closed for the stopping of the engine and the said safety stop device is operative only when the driving connections between the governor and said engine become broken or in- 130

operative and when the working parts of the engine become damaged and unduly affect the operation of the engine.

In the working of the automatic safety 5 stop device in connection with the governor and the engine, the normal position of the safety device has the weighted arms 8 and 9 thereof disposed perpendicularly as shown in full lines in Figs. 2 and 4 of the drawings 10 so that the governor stem G will operate in the usual well-known manner when the engine is started and operated under normal conditions. When starting the engine, the throttle valve stem 20, is worked outwardly 15 in the throttle valve casing H to open the throttle valve therein, so that the engine will be supplied with steam in the ordinary well-known manner. On the opening of the throttle valve by manually operating the 20 valve stem 20, the collar 21 on the latter is brought into engagement with the setting rod 14, so that the latter is shifted to bring the latch or catch 13 into position for the engagement thereof with the horn 11 on the 25 swinging arm 9, when in its perpendicular position, and also to locate the said latch or catch 13 in the path of movement of the tripping cleat or cross head 23 on the governor stem G.

30 When the engine is working under ordinary conditions, the governor is operated to control the speed of the engine. Now should the driving connections between the engine and the governor become disturbed, broken 35 or otherwise ineffective, the governor stem G of the governor lowers to an abnormal degree, by the governor arms C dropping so that the tripping cleat or cross-head 23 will act directly upon the tripping latch or catch 40 13, rocking it upon its pivot causing said latch or catch to act upon the horn 11 at the beveled nose 12 thereof for initially moving the arm 9 causing it to swing outwardly and under the action of the trip 45 weight 10' thereon the same will drop downwardly from perpendicular position to that shown in Fig. 1 of the drawings by full lines and by dotted lines in Fig. 4 of the drawings. During the movement of the arm 9, corre- 50 sponding movement is imparted to the arm 8 due to the meshing engagement of the toothed sectors 6 and 7 and in the movement of the arm 9 it engages the striking head 22, whereby corresponding movement will be 55 imparted to the arm 3, which through its connection with the rocking beam 28, causes the shifting of the latter and the rods 29 so that through the connection of the latter with the arms 30 the controlling valves of 60 the engine will be brought to closed position thus closing off steam to the engine, notwithstanding the fact that the throttle valve remains open. In the movement of the arm 8 the compound lever 24 is actuated and acts 65 against the arm 26, which is connected with

the governor stem G causing the latter to be moved upwardly and thereby swinging the governor arms C with the weighted members D thereon outwardly and in this manner the governor is actuated to abnormally 70 burden the engine for retarding the speed of the working parts thereof so that the same will be brought to a quick standstill. It is of course understood that in the use of the automatic safety stop device the same 75 is manually set to bring it to normal inactive position with the arms 8 and 9 thereof, disposed perpendicularly as shown by full lines in Figs. 2 and 4 of the drawings, the governor being active under normal conditions with the engine in the usual manner and said safety stop device becomes operative only when abnormal conditions arise or the connections between the governor and said engine become ineffective, broken or 80 damaged.

85 Mounted on the stand post or column A of the governor are suitable shock absorbers 34, disposed in the path of movement of the sectors 6 and 7 so that on the dropping of 90 the arms 8 and 9 of the safety stop device, the said sectors 6 and 7 will engage with the shock absorbers to limit the dropping movement of the said arms 8 and 9 under the burden of the weights 10 and 10' thereon and 95 in this manner the governor arms will not be unduly burdened when the safety stop device is active.

95 Manifestly, the construction shown is capable of considerable modification and 100 such modification as is within the scope of my claims, I consider within the spirit of my invention.

I claim:-

1. In combination with the speed governing means of an engine, weighted pivotal means supported on the engine, trip means engaged with the weighted means and operable upon movement of the speed governor's stem for actuating the same, cut-off valve 105 operating means, and means connected to said cut-off valve operating means adapted to be actuated by the pivotal weighted members upon their release for moving the cut-off valve to closed position.

110 2. In combination with the cut-off valve and the speed governing means of an engine, said cut-off valve having connection with the stem of the governing means, weighted pivotal means supported in proximity to the governing means, trip means engaged with the weighted means and operable upon movement of said governor stem for actuating the same, and means engaged by said arms upon movement to their lowermost positions for 115 causing operation of the cut-off valve connection and permitting the valve to be moved to its closed position.

120 3. In combination with the cut-off valve and speed governing means of an engine, a 125

releasable connection engageable with the cut-off valve and connected to the stem of said governing means, a plurality of interconnected pivotal weighted members supported in proximity to said governing means, trip means engaged with one of said pivotal members and operable upon movement of the speed governor stem for actuating the same, and means engaged with the remaining pivotal member adapted to be engaged with and operate said cut-off valve connection upon movement of the pivotal members to their lowermost positions.

4. In combination with the throttle valve, 15 cut-off valve and speed governing means of an engine, a pair of pivotal weighted arms supported in proximity to said governing means, slidable trip means actuated upon movement of the throttle valve for connecting one of the pivotal arms to the stem of the speed governing means, said stem being adapted to disengage the slidable tripping means upon the presence of abnormal conditions, means operated by said pivotal 20 weighted arm for imparting motion to the remaining pivotal weighted arm, operating means connected to said cut-off valve, and

means connected to said remaining pivotal weighted arm adapted to be engaged with the cut-off valve operating means upon 30 downward movement thereof for causing said cut-off valve to be moved to its closed position.

5. In combination with the throttle valve, cut-off valve and speed governing means of 35 an engine, a pair of interengaged pivotal weighted arms mounted in proximity to said governing means, slidable spring pressed tripping means supported adjacent one of said arms and operated upon movement of 40 the throttle valve for releasably connecting said arms to the stem of the governing means, a rotatable trip engageable with the cut-off valve, cam means engageable with said rotatable trip having pivotal connection 45 with the stem of the governing means, and means connected to the remaining pivotal weighted arm engageable with said cam operating means upon movement of the same to its lowermost position for causing said 50 cut-off valve to be moved to closed position.

In testimony whereof I affix my signature hereto.

GUSTAV J. SELK.
